W. B. COSBY.

GLAZIER'S TABLE.

APPLICATION FILED NOV. 10, 1907

926,470.

Patented June 29, 1909.

UNITED STATES PATENT OFFICE.

WILLIAM B. COSBY, OF KANSAS CITY, MISSOURI, ASSIGNOR OF ONE-HALF TO ZACHARY TAYLOR, OF HOUSTON, TEXAS.

GLAZIER'S TABLE.

No. 926,470.

Specification of Letters Patent.

Patented June 29, 1909.

Application filed November 19, 1907. Serial No. 402,795.

To all whom it may concern:

Be it known that I, WILLIAM B. COSBY, a citizen of the United States of America, residing at Kansas City, in the county of Jackson, son and State of Missouri, have invented certain new and useful Improvements in Glaziers' Tables; and I do hereby declare that the following is a full, clear, and exact description of the invention, such as will enable others to make and use the same, reference being had to the accompanying drawing, forming a part of this specification.

The object of the invention is a table, upon any portion of the top of which, window glass of varying proportions may be securely held in position while being assembled in panels or cut the requisite size.

The invention consists in the novel construction and combination of parts such as will be first fully described, and then specifically pointed out in the claims.

In the drawings: Figure 1 is an isometric view of a table embodying the invention. Fig. 2 is a plan view of the table, showing the invention, and an art glass window panel with the parts assembled. Fig. 3 is a transverse vertical sectional view of the table taken upon the line x, x , on Fig. 1. Fig. 4 is a detail view in perspective of the arm or holder for the glass on the table. Figs. 5 and 6 are detail views in perspective of alternate constructions of the holder arm, seen in Fig. 4. Fig. 7 is a detail view in perspective of the sliding clamp for the holder arms. Figs. 8, 9, 10 and 11 are side, end, perspective and plan views, respectively, of an alternative construction of the clamping device for the holders for the glass seen in Fig. 7. Fig. 12 are end views of contiguous strips forming part of the table top, showing the grooves wholly within the contiguous strips.

Similar numerals of reference indicate corresponding parts in all the figures of the drawing.

Referring to the drawing: 12 indicates the improved glazier's table top or bed, which consists of separate strips, 14, of wood or other suitable material of a uniform length. These strips are narrow in width and are arranged at slight distances apart, so as to form the slots, 15, between contiguous strips 14. The strips 14 are secured rigidly at their ends to the upper surface of the longitudinal strips or bars, 16, these bars being made of any desired length. Between the outer strips 16 is

an intermediate strip, 16^x, which extends parallel with the strips 16, and to which the strips 14 are also secured, the intermediate strip serving to support the central portion of the table top. In the upper surface of the beams 16, 16^x, beneath the slots 15, are transverse notches, 17, these notches being extended in length and a slight distance beneath the lower surfaces of contiguous strips 14.

Extending in the longitudinal direction of the table top and secured rigidly to the outer surface of one of beams 16, is a narrow strip, 18, the upper portion of which strip extends a short distance above the horizontal line of the upper surface of the table top. A strip, 19, extends transversely to the table top and is secured rigidly to the ends of the bars 16, 16^x, at one end of the table, the end of the strip 18 and that of strip 19, which are adjacent to each other at one corner portion of the table, being mitered together at 20.

The holder for the glass consists of a bar or straight piece of metal or wood, 21, the portions of the sides of which bar at its forward end 22 are inclined inwardly at an angle to the rear end of said bar, the extreme end being rounded at 23, which end 23 is brought in contact with the glass and therefore extends upwardly a distance corresponding to the thickness of plate or cathedral glass. In the rear end of the bar is a longitudinal slot, 24. The clamping device for the holder consists of an upper plate 25, and a lower plate, 26, the plates being short in length and slightly wider than the slot 15, in the table top. These plates are secured together at the ends by the pins, 27, (see Fig. 7) the pins being slightly longer than the distance from the upper to the lower surface of the strips 14. A separate pin, 28, is connected at its lower end with the lower plate 26, intermediate the pins 27, the upper end of which pin 28 extends through the upper plate 25, and a considerable distance upwardly from the line of the upper surface of said plate and is screw threaded as at 29. The clamping plates are connected to the table top by inserting the pins, 27, of the clamp within the slot 15, the lower plate passing readily within the notch 17, in the supporting bar 16, and the upper bar 25, being slidable upon the upper surface of the table and movable longitudinally in line with the slot 15. The slotted bar or holder 21 is placed in position on

- the plate 25, the screw threaded end of pin 28 extending within the slot 24 of the bar or holder 21. Upon the said screw threaded end of pin 28, is fitted a thumb nut 30, which 5 clamps the bar 21, and holds the same adjustably in position. The slots in the table top are provided with the clamps and holders in suitable number, and the holders may be of different lengths, if preferred.
- 10 For the purpose of holding ordinary window glass in position while being cut the requisite length, the glass is placed in one corner of the table top and with one end against the end strip 19 and the longer portion 15 close in position to the inner surface of the strip 18. The thumb nut 30 being loosened on the pin 28 of the clamp, the end 23 of the bar 21 is moved so as to come firmly into contact with the longer portion of the glass 20 opposite to that in contact with the strip 18, on the table top, and the thumb nut turned so as to clamp the bar firmly to plate 25. In this position of the bar 21, the glass is prevented from moving while being squared at 25 its outer end or cut into various sizes, an ordinary scale being conveniently made on the strips 18 and 19.
- For the purpose of holding fractional portions of art glass in the construction of windows of such material, it has been the custom heretofore to employ nails to hold the fractional portions of a panel in position upon the table top. After a time, the repeated penetration of the wood by the nails 30 breaks the fiber and the nails fail to hold the portions of the glass in position in the panel. In the present invention, any degree of firmness may be obtained necessary to hold the glass in position, and at any angle, the adjustment being quickly obtained of the bar 35 21, and without danger of breaking the glass, which frequently occurs in driving the nails in the securing of the glass upon the ordinary glazier's table.
- 40 As shown in Fig. 2, which illustrates an art panel upon the table top, the holders, 21, are shown, obtaining a purchase radial to the pin 28. Many of the fractional portions of the 45 cut glass, when placed in position, require a direct pressure and at the same time not obstruct the work. For this purpose, I employ the holders as seen in Figs. 5 and 6. Upon the rear ends of these holders are hubs 31 50 perforated at 32 to receive the threaded pin 28. The arm 33 of the holder in Fig. 5 ex-

tends from the hub 31 upon a line tangential to the pivot opening 32, the forward end of said arm and the arm 33* in Fig. 6 decreasing gradually in width in the direction of the outer end, the upper portion of said end in Fig. 6 being flat while the upper surface in Fig. 5 is similar to the upper surface on Fig. 4. Instead of the clamping device for the holder as seen in Fig. 7, I employ the modification seen on Figs. 8, 9, 10 and 11. In this construction, the vertical plate 34 is made to slide in the slots 15 of the table top. The screw 35 passes downwardly through the perforate rear end of the holder and within a screw threaded transverse opening, 36, in 70 the plate, the outer surfaces of the screw being flat and in the same plane with the outer surfaces of the plate 34. Upon the upper end of the screw is a flat head, 37, by means of which the screw is operated. In a 75 half way turn of the screw 35, the portions of the threads in the threaded portions of the transverse opening 36, are extended outwardly and grasp the sides of the slot 15.

The table top may be supported by trusses 80 or in any other suitable manner and the top extended in length and width.

It is obvious that the adjustable holders may be arranged upon the table so as to grasp the glass from opposite directions and 85 the strips 18 and 19 employed or not, as preferred. Instead of the notches 17 in the bars 16, grooves 40 may be made in the separate strips composing the table top as seen in Fig. 12, and such other modifications employed as 90 are within the scope of the invention.

Having fully described my invention, what I now claim as new and desire to secure by Letters Patent is:

1. A glazier's table provided with grooves 95 in the table top, sliding devices in said grooves, clamping devices carried by the sliding devices, a hub, and holding arms for the objects on the table connected with and extending tangentially to the hub. 100

2. In a glazier's table, the combination with the table top having grooves, of sliding clamping devices within said grooves, hubs pivotally connected with the clamping devices and arms connected with and extending tangentially to said hub. 105

WILLIAM B. COSBY.
